(57) **CLAIM**

The ornamental design for a compressor, as shown and described.

DESCRIPTION

FIG. 1 is a front elevational view of the compressor showing our new design, in which the elements shown in broken lines form no part of the design;

FIG. 2 is a top plan view of the design, in which the elements shown in broken lines form no part of the design;

FIG. 3 is a rear elevational view of the design, in which the elements shown in broken lines form no part of the design;

FIG. 4 is a bottom plan view of the design, in which the elements shown in broken lines form no part of the design;

FIG. 5 is a right side elevational view of the design, in which the elements shown in broken lines form no part of the design;

FIG. 6 is a left side elevational view of the design;

FIG. 7 is a front elevational view of a second embodiment of the design, without broken lines;

FIG. 8 is a top plan view of the second embodiment;

FIG. 9 is a rear elevational view of the second embodiment;

FIG. 10 is a bottom plan view of the second embodiment;

and,

FIG. 11 is a right side elevational view of the second embodiment, the left side elevational view of the second embodiment being the same as shown in FIG. 6.
